UNITED STATES PATENT OFFICE.

ROBERT BUEDINGEN, OF ROCHESTER, NEW YORK.

CONTAINER.

Application filed April 8, 1922. Serial No. 550,660.

To all whom it may concern:

Be it known that I, ROBERT BUEDINGEN, a citizen of the United States, residing in the city of Rochester, county of Monroe, and 5 State of New York, have invented certain new and useful Improvements in Containers, of which the following is a full, clear, and exact specification.

My invention relates to containers and refers particularly to jointure means for 10 containers.

In the production of containers, particularly those made of cardboard, it is desirable, for purposes of manufacture, that the 15 side member of the container be separate from the bottom member and that the two be affixed, or joined, together to obtain the container.

It is obvious, therefore, that in order that 20 the container be perfectly adapted for the enclosure of fine powder, the jointure between the side member and the bottom member must be a complete and perfect one.

Many processes have been suggested for 25 the accomplishment of this desirable result, but they have been generally found inoperative on account of their failure to produce a perfect joint, or uncommercial on account of their cost of production.

30 The device of my invention overcomes all of the objectionable features of the former proposed methods and presents a means whereby a perfect, complete and lasting jointure may be obtained economically.

35 In a broad way, my device comprises a bottom, having extended sides, with a smaller interiorly positioned step, to which a paper, or other flexible, sealing member is partially attached, the elements being so shaped 40 and positioned that the side member of the containers can be affixed to the unattached portion of the sealing member and forced downwardly into the space between the step and the bottom sides.

45 It is evident that any irregularities in the bottom portion of the side member of the container will fit itself absolutely to the loose flexible sealing member, thus forming a perfect jointure. This cannot be accomplished where the irregular edge of the side member is brought into abutment with a stiff cardboard bottom, as there will be no flexibility in either element to accommodate 50 itself to such irregularities, and hence, a perfect jointure can not be obtained.

Further, jointures made between two non-

flexible elements are not of a lasting character and are easily disjointed and separated by the wear and tear of shipment and use. Such, however, is not the case where a non- 60 flexible element is joined to a flexible one, as the latter will allow of considerable movement without breakage of the jointure.

It is also evident that the positioning of the side member between the step and the 65 side of the bottom, while attached to the flexible member, produces a still more positive and stable jointure, and one which is so perfect as to prevent the leakage of the finest powder.

70 In the accompanying drawings, illustrating one form of the device of my invention, similar parts are designated by similar numerals.

Figure 1 is a perspective view of a bottom 75 member.

Figure 2 is a perspective view of a step.

Figure 3 is a top plan view of a bottom member and step.

Figure 4 is a top plan view of a paper seal- 80 ing member.

Figure 5 is a top plan view of the bottom member, step and sealing member, partly broken away.

Figure 6 is a perspective view of the side 85 member inserted in the assembled bottom members.

Figure 7 is a broken vertical cross-section of Figure 6.

The particular form of the device of my 90 invention, shown in the accompanying drawings, comprises a bottom member having the bottom 10 and the sides 11, 11, 11, 11, the edges thereof being made dust-proof by means of a surrounding paper 12 covering 95 the same.

A card board step 13, having glue upon its one side, is attached to the central portion of the bottom 10, the cardboard 13 being of such size that it will leave an uncovered space around the sides of the bottom 10, thus forming the recess 14.

100 A paper sealing member 15 is then attached at its central portion 16 to the step 13, the remaining portion of the sealing 105 member being free from such attachment. The sealing member is approximately the size and shape of the bottom 10.

110 As thus constructed, the bottom member consists of a bottom 10, having sides 11, the joints of which are closed by an outside paper 12 attached thereto, a smaller step 13

carried by the inside face of the bottom, and a paper sealing member 15 attached at its central portion to the step, the free portion extending over the recess formed by the 5 step, the bottom and the sides.

The sides of the container of the illustrated device consist of the angularly folded cardboard member 17, to the inside of which is attached the folded cardboard member 18, 10 this particular construction being illustrated simply as a means of showing a side member in which the angles are dustproof.

The lower edges of the side member 17, 18 are inserted into glue 19 and the side 15 member then inserted into the bottom member and pressed downwardly. The lower edges of the side member 17, 18 are thus brought into contact with the loose portion 20 of the sealing member 15 and forced downwardly into the recess 14.

If desirable, glue may be placed upon the lower exterior faces of the container sides 17, 18, which will affix the side to the interior faces of the bottom sides 11, 11.

25 It is evident that a complete jointure of the side member 17, 18 and the sealing device 15 will thus be accomplished, the free portion of the latter, not being fixedly attached to the step 13, will accommodate itself 30 to any inaccuracies of the side member 17, 18, and thus an absolutely dust-proof jointure is produced, and material placed within the container can not escape, or sift out, through the bottom thereof.

35 No cover is shown in the illustrations, as that portion of the container is not an element of this application.

It is evident that the container may be 40 round, oval or of other desirable shape, and that the step may be an integral portion of the bottom, or can be produced by an inward pressure on the bottom, as well as of the design illustrated.

I do not limit myself to the particular 45 size, shape, number, quality or arrangement or parts as shown in the drawings which are given simply as a means for the clear explanation of my invention.

What I claim is:—

1. In a container, in combination, a bottom carrying side members, a raised step carried by the bottom, a flexible sealing member partially attached to the bottom and a container side member attached to the unattached portion of the sealing member. 55

2. In a container, in combination, a bottom carrying side members, a raised step, smaller than the bottom, carried by the bottom, a flexible sealing member partially attached to the bottom and a container side member attached to the unattached portion 60 of the sealing member. 60

3. In a container, in combination, a bottom carrying side members, a raised step, smaller than the bottom, carried by the bottom, a flexible sealing member partially attached to the bottom and a container side member attached to the unattached portion 65 of the sealing member between the edge of the step and the bottom side. 70

4. In a container, in combination, a bottom carrying side members, a raised step carried by the bottom and spaced from the bottom sides, a flexible sealing member of the approximate size of the bottom and 75 centrally attached to the step, the outer portions of the sealing member being unattached and a container side member attached to the unattached portion of the sealing member. 80

5. In a container, in combination, a bottom carrying side members, a raised step carried by the bottom and spaced from the bottom sides, a flexible sealing member of the approximate size of the bottom and centrally attached to the step, the outer portions of the sealing member being unattached and a container side member attached to the unattached portion of the sealing member and within the space between 90 the step and the bottom side. 90

Signed at Rochester, in the county of Monroe and State of New York, this 4th day of April, 1922.

ROBERT BUEDINGEN.
